UNITED STATES PATENT OFFICE.

REUBEN BELL, OF NEW YORK, N. Y.

MACHINE FOR MAKING HAT-LININGS.

1,360,870.

Specification of Letters Patent. Patented Nov. 30, 1920.

Application filed June 10, 1919. Serial No. 303,095.

To all whom it may concern:

Be it known that I, REUBEN BELL, a citizen of the United States, and a resident of the city of New York, borough of Manhattan, in the county and State of New York, have invented a new and Improved Machine for Making Hat-Linings, of which the following is a full, clear, and exact description.

10 This invention relates to machinery for producing hat linings and has for an object to provide an improved construction associated with an ordinary sewing machine whereby a lining member may be quickly 15 and accurately formed.

Another object in view is to provide an attachment for sewing machines which may be easily manipulated for cutting strips of cloth into certain lengths after passing 20 through the sewing machine and then cutting draw strings of a different length.

In the accompanying drawings:

Figure 1 is a top plan view of the device embodying the invention.

25 Fig. 2 is a section through Fig. 1 on line 2—2.

Fig. 3 is a section through Fig. 1 on line 3—3.

Fig. 4 is an edge view of the cutting device and guide therefor shown in Fig. 3.

Fig. 5 is a plan view of part of a strip of cloth after the same has been severed by the knife shown in Fig. 3.

Fig. 6 is a view similar to Fig. 5 showing 35 the severed cloth and the tape carried thereby moved a certain distance.

Fig. 7 is a view similar to Fig. 6, but showing the tape severed for producing projecting ends.

40 Fig. 8 is a plan view of a section of cloth having a hem and tape arranged in the hem with the ends projecting.

Referring to the accompanying drawings by numerals 1 indicates a sewing machine 45 of any desired kind which is provided with a hemmer 2 of any desired kind for producing the hem 3 in the strip of cloth 4. In producing hem 3 a tape 5 is inserted therein during the hemming operation, as shown 50 in Fig. 1.

The operation just described of providing a hem and inserting a tape at the same time is old and well known and forms no part of the present invention, except in combina-

tion with the parts hereinafter fully described.

In making hat linings a section of cloth must be provided having a hem on one edge and a tape therein with ends projecting beyond the cloth, whereby said ends may be 60 grasped and the cloth drawn in order to pucker the same and produce the proper shape and size of the crown of the lining. In order to form lengths of cloth in the strip 4 having projecting ends of tape a 65 cutter 6 is provided which is pivotally mounted on the bracket 7 which in turn is rigidly secured by screws or other means to the table of the sewing machine 1. A spring 8 is connected with one end of the cutter 6 and to a fixed hook or other support as shown in Fig. 3 so that the cutter will normally be held in an elevated position as shown in Fig. 3. This cutter is provided with a knife 9 removably held in position 70 by suitable screws 10 whereby the knife may be disconnected at any time and sharpened or replaced by a new knife. The knife 9 contacts with a suitable stationary knife 11 connected with the bracket 7 as shown in Fig. 80 2, so that there will be a shearing action for cutting the cloth 4. The knife 9 is positioned to cut from the edge of the hem 3 to the opposite side of strip 4 as indicated in Fig. 5. This leaves the hem uncut and also 85 leaves the tape 5 uncut. However, as the hem is small and the tape 5 is comparatively strong a slight pull against the hem on the severed section 4' of strip 4 will cause the hem to be torn in two and opposite the cut 90 12. Preferably the hand of the operator bears against the strip 4 and hem 3 near the hemmer during this pulling operation. The pressure of the hand of the operator, however, is not directly or squarely on the hem 95 3, as the tape 5 is allowed to slip through this hem as each section 4' is pulled until it is separated as shown in Fig. 6. After it has been separated in this manner it is 100 swung over slightly until the tape comes 105 under the knife 9 and the knife is again lowered for cutting the tape as shown in Fig. 7. This completes the operation of making one hat lining and at the same time leaves a projecting end on the main body of 105 the strip 4 and the next section 4'. After the first section 4' has been made in the manner just described it is thrown to one side and the hemming operation is continued

until the strip 4 has reached the arrow 13 and then the cutting and pulling operation is again carried out for the second time. This method is used continually during the 5 operation of the device. The arrow 13 is, of course, positioned to indicate the desired length of the lining and may be moved pivotally on its support to a number of different positions, and when once set left in that 10 position, until a different sized lining is desired.

In order that the section 4' may be held in proper position and fed in a straight line through the machine, a supporting belt 14 15 is provided supported by a small freely rotating roller 15 carried by the bracket 7 and supported at the opposite end by a comparatively large roller 16 carried by a shaft 17. This shaft is supported by any suitable 20 form of standard 18. A comparatively large pulley wheel 19 is connected to shaft 17 so as to rotate the roller 16, said pulley wheel accommodating a belt 20, which belt also passes over a suitable pulley wheel 21 operated from any suitable power, as for instance motor 22, which also operates the 25 sewing machine. These pulleys are so proportioned and also the roller 16 is so proportioned that belt 14 will move at the same 30 speed that the strip 4 is fed through the sewing machine. When the section 4' has reached the arrow 13 the sewing machine is stopped, which will also stop the belt and pulley, the cutting operation is then carried 35 out after which the sewing machine is started and the other parts automatically move in proper relationship therewith.

As shown in Fig. 4 the cutter 6 is guided in its movement by the plates 23 and 24, 40 which plates are each provided with an arc-shaped slot 25 for accommodating the screw 26 which is threaded into the cutter 6 and extends through these slots. The length of

the slot 25 limits the upward and downward movement of the cutter and the plates 45 23 and 24 prevent any lateral movement. This allows the operator to quickly press on the handle 27 for the cutting operation desired and carefully let go and the spring 28 will move back the cutter to its proper ele- 50 vated position.

What I claim is:

1. In a device for producing lengths of hemmed cloth having a tape extending through the hem and beyond each end of the 55 cloth, the combination with a sewing machine for producing a hem and applying tape in the hem simultaneously, of a belt for receiving the hemmed cloth from the sewing machine, said belt acting as a table 60 on which to manipulate the cloth, a cutter arranged adjacent one end of the belt positioned to cut the cloth without cutting the hem on the first operation, said cloth being positioned so as to be manually moved to a 65 second position whereby the tape may be cut at a distance from the cloth on a second operation, said cutter being offset with relation to the line of feed sufficiently to fail to cut the hem on the first cutting operation. 70

2. The method of producing lining formed with a hem on one edge and a tape extending therethrough and beyond each end comprising the provision of a strip of cloth in open width forming a hem thereon, applying a 75 tape in the hem as the hem is formed, cutting off predetermined lengths of the hemmed strip except the hem, pulling against the hem until it breaks in line with the severance of the strip, said pulling action continuing until a section of said tape connects the two sections of cloth, and then cutting said tape at a point substantially midway between said sections of cloth. 80

REUBEN BELL.
